UNITED STATES PATENT OFFICE.

ARTHUR NEWTON, OF BOSTON, MASSACHUSETTS.

STREET-RAILWAY CAR.

1,117,692.

Specification of Letters Patent. Patented Nov. 17, 1914.

Application filed March 23, 1914. Serial No. 826,787.

To all whom it may concern:

Be it known that I, ARTHUR NEWTON, a citizen of the United States, and resident of West Roxbury, Boston, in the county of 5 Suffolk and State of Massachusetts, have invented certain new and useful Improvements in Street-Railway Cars, of which the following is a specification.

This invention has for its object to enable 10 the operator of a street railway car, who is called the motorman when the car is electrically impelled, to occupy such position when performing his usual functions, that he is able also to reach out into the space immediately 15 above the usual fender or guard which projects from the front end of the car, and pull a person encountered by the fender or by the car to a safe position on the fender or the car, or push the person 20 aside out of danger.

The invention is embodied in a street railway car having an operator's station the platform or floor of which is depressed below the floor of the car and into such proximity 25 to the track that the operator standing on said floor while performing his usual functions occupies a position enabling him to also perform the rescue work above indicated.

30 Of the accompanying drawings forming a part of this specification; Figure 1 represents an end elevation of a street car embodying my invention; Fig. 2 represents a side elevation of a portion of the car; Fig. 35 3 represents a top plan view of a portion of the car; Fig. 4 represents a longitudinal section of a part of a car showing a supplemental floor or platform.

The same reference characters indicate the 40 same or similar parts in all the views.

In the drawings, 12 indicates the body of a street railway car which as here shown is provided with side entrances 13 near the ends of the car.

45 The general level of the floor of the car is indicated at 15 (Figs. 1 and 2), the floor being located above the running gear of the car as usual.

16 represents a fender which may be of 50 any suitable construction and projects from the front end of the car.

In carrying out my invention I provide a 55 depressed floor or platform 14 on which the operator or motorman stands when operating the car. Said platform supports the usual controller, the brake-operating device,

and other instrumentalities usually provided on a street car platform for the use of the operator in running the car. As shown by Figs. 1 and 2, the platform 14 is considerably below the level of the floor 15 and is located substantially flush with the fender and as close to the track as is possible without liability of contact with the track when the car body moves vertically. The position 60 of the operator standing on the platform 14 is such that he is able, without leaving his post, to reach into the space immediately above the fender 16 and perform such rescue work as may be needed. In other words, the 65 operator is able to rescue or help a person in danger of being injured by the car.

The space above the depressed platform 14 may be inclosed or not. As here shown, the depressed platform is the floor of a small 70 compartment having oblique sides 17, and a back or partition 18 separating the compartment from the interior of the car. The front of the compartment has an opening sufficiently large to permit the operator to project his body or the upper part of it into the space above the fender. I have here shown the front of the compartment formed by doors 19 hinged at 20 and adapted to be 75 opened outwardly to permit the operator to 80 perform rescue work. The compartment may have a displaceable front of any other suitable construction adapted to shield the operator and to be quickly displaced to permit the operator to act in the space in front 85 of the compartment.

When the car has a transverse buffer extending across its end to sustain shocks incidental to collisions, such buffer being usually at about the same height as the floor 15, 90 the depressed operator's platform is below the buffer, as indicated by Figs. 1 and 2, where the buffer 21 is represented by dotted lines. The buffer thus located would extend across the front of the operator's compartment above the floor 14 and the displaceable front formed by the doors 19 or otherwise will be entirely above the buffer. The height of the buffer above the depressed floor 14 is not sufficient to interfere materially with rescue work by the operator, who is enabled by the depressed platform to lean 100 outwardly across the buffer.

A depressed platform 14 will usually be provided at each end of the car, and the 110 space or inclosure above it will preferably communicate with the interior of the car by

- suitable doors, which may form the partition 18 above described. To enable the said inclosure to be utilized at the rear end of the car, a supplemental platform 23 (Fig. 4) 5 may be removably supported above the depressed platform 14 and flush with the floor 15, said supplemental platform being transferable, if desired, from one end of the car to the other, and used only at the rear end. 10 When the doors at 18 are opened, the supplemental platform 23 constitutes an extension of the floor 15 on which the conductor and passengers may stand. The supplemental platform may be supported by 15 cleats 24 attached at suitable points to the car above the depressed platform 14.

The space extending from the track upwardly at the front of a moving car is what I call the danger space, because a person in 20 this space is exposed to great danger. The platform 14 is depressed so far below the floor of the car and into such proximity to the track that the motorman can reach practically all parts of this space without 25 leaving his post.

Having described my invention, I claim:

1. A street car having an operator's platform depressed below the level of the floor of the car and in such proximity to the 30 track as to enable the operator to perform rescue work in the danger space at the front of the car without leaving his post.
2. A street car having an end compartment for the operator, having a floor depressed below the level of the floor of the 35 car and in such proximity to the track as to enable the operator to perform rescue work in the danger space at the front of the car without leaving his post.

car and in such proximity to the track as to enable the operator to perform rescue work in the danger space at the front of the car without leaving his post, and a front opening affording direct access to said space. 40

3. A street car having a forwardly projecting fender and an operator's platform depressed below the level of the floor of the car and practically flush with the fender, whereby the operator or motorman is enabled to perform rescue work at the front end of the car without leaving his post. 45

4. A street car having a forwardly projecting fender and an end compartment for the operator, said compartment having a 50 floor depressed below the floor of the car and practically flush with the fender and a front opening affording access by the operator to the space immediately above the usual location of a fender, at the front end 55 of the car without leaving his post.

5. A street car having an end compartment for the operator, said compartment having a platform depressed below the floor of the car, and a supplemental platform removably supported above the depressed platform and substantially flush with the floor of the car. 60

In testimony whereof I have affixed my signature, in presence of two witnesses.

ARTHUR NEWTON.
